Inventor:

Edward L. Kraus.
His ATTORNEY
G. G. Oettinger

UNITED STATES PATENT OFFICE.

EDWARD L. KRAUS, OF SLATINGTON, PENNSYLVANIA.

SCHOOL-SLATE.

SPECIFICATION forming part of Letters Patent No. 320,367, dated June 16, 1885.

Application filed January 19, 1885. (No model.)

To all whom it may concern:

Be it known that I, EDWARD L. KRAUS, a citizen of the United States, of the borough of Slatington, in the county of Lehigh and State of Pennsylvania, have invented certain new and useful Improvements in School-Slates, of which the following is a specification.

The invention relates to improvements in school-slates; and it consists, essentially, in securing firmly to the edge of the slate-frame some inexpensive soft or elastic material which will deaden the noise of the motion of the slate.

It further consists in the construction and novel arrangement of certain parts herein-after described, and pointed out in the appended claims.

In the accompanying drawings, Figure 1 represents a plan view of a slate with the invention attached. Fig. 2 is a cross-section of the two cords or bundles of cords, forming part of the invention. Fig. 3 is a plan view of the same, showing the web uniting the two cords or bundles of cords. Fig. 4 is a plan view of a part of a metal strip, forming part of the invention. Fig. 5 is a transverse section of a slate-frame. Fig. 6 is a view of a part of the slate so sectioned as to show the invention attached to the frame. Fig. 7 is a cross-section of the slate frame with the invention attached. Fig. 8 is a similar view of the same, with a modification of the invention attached.

Referring to the accompanying drawings by letter, A designates the slate-frame inclosing the slate A'. The outer edge of the slate-frame is provided with the longitudinal groove, D, shown in section in Fig. 5. B B are similar endless cords or rolls, consisting of any suitable number of united cords the united diameters of which are somewhat greater than the thickness of the slate-frame. The said cords or rolls are made of any cheap soft or elastic material, rubber being preferable, and are secured together side by side by a longitudinal web or by transverse uniting-cords. The preferable way of securing the cords or rolls together is by a cord, E, Fig. 5, which slants alternately from the one to the other, and has its bends well secured in the substance of the cords B.

C is a metallic strip, preferably of tin, convex in transverse section, and of somewhat greater width than the groove D in the slate-frame. The web E is of such width that when bent down against the sides and bottom of the groove D the cords or rolls, B, will be drawn forcibly together.

The manner of securing the invention to the frame is as follows: The web E is laid over the groove D, with the cords or rolls B resting on the corners of the edge of the slate-frame. The strip C is then bent more convex, so that it can be readily introduced with its concave side downward into the groove D above the web E. When the strip is at the bottom of the groove, it is released, and, springing outward, its edges bind the web against the sides of the groove, as shown in Fig. 7. The strip might be introduced with its convex surface downward, and would hold the web; but the former manner holds the web tighter. When the cords or rolls B are thus secured to the frame, their adjacent sides impinge on each other, and the outer sides stand outward beyond the sides of the slate-frame. Thus the edge and sides of the frame are prevented from making noise by contact with the desk.

In the modification shown in Fig. 8 the cords or rolls B are replaced by the cords b, much smaller in diameter. w is a cord sufficient in diameter to drive the outer sides of the cords, when pressed between the latter, outward beyond the sides of the slate-frame. The cord w is covered by the felting g, or other suitable material, and the strip C is inserted between the cord and felting, as shown. The strip acts so as to bind both the felting and web E against the sides of the notch D.

I am aware that muffling material in cord form, has been attached to school-slate frames by means of notches formed therein, and such construction I do not claim, broadly; but,

Having described my invention, I claim—

1. The combination, with the frame of a slate having a longitudinal recess or notch around its edge, of endless cords of soft elastic material the diameters of which united have a greater width than that of the frame, and

webs uniting the said cords of sufficient width when secured within the notch adjacent to its bottom and sides to hold the cords down on the edge of the slate-frame with their adjacent sides pressed together, substantially as specified.

2. The combination of the frame A, provided

with the notch or recess D, with the cords or rolls B, web or uniting-cord E, and spring-strip C, substantially as specified.

EDWARD L. KRAUS.
